UNITED STATES PATENT OFFICE.

THOMAS CRAWFORD, OF GREEN ISLAND, NEW YORK.

CAR-TRUCK.

SPECIFICATION forming part of Letters Patent No. 571,263, dated November 10, 1896.

Application filed May 8, 1896. Serial No. 590,719. (No model.)

To all whom it may concern:

Be it known that I, THOMAS CRAWFORD, of Green Island, in the county of Albany and State of New York, have invented certain new and useful Improvements in Car-Trucks; and I do hereby declare that the following is a full, clear, and exact description thereof, reference being had to the accompanying drawings, and to the letters of reference marked thereon, which form part of this specification.

This invention is an improvement in trucks for electric-railway cars, and it has especial reference to the particular structure of the truck and to the mounting of the car-bodies thereon, as will be clearly understood from the following description and the accompanying drawings, in which—

Figure 1 is a side elevation of a complete truck and portion of car-body mounted thereon. Fig. 2 is an end view thereof. Fig. 3 is a detail section on line 33, Fig. 2. Fig. 4 is a detail vertical section on line 44, Fig. 2. Fig. 5 is a top plan view of one of the corner castings. Fig. 6 is a detail view of the spring-supporting swinging links. Figs. 7, 8, 9, and 10 are detail views of modifications of the pedestals and springs. Fig. 11 is a view of a modification of the main bolster-spring connection. Fig. 12 is a detail of the main bolster-spring connection to car-body. Fig. 13 is a detail of the brace-adjusting wedge. Fig. 14 is a transverse section on line 1414, Fig. 1. Fig. 15 is a detail of one of the end braces.

The top side bars of the truck-frame are composed of two metal bars A A, set edgewise and secured to the upper ends of pedestals B B by bolts a a, as shown. The bars A extend beyond the pedestals at both ends of truck, and are united at their extremities to corner castings C by bolts a'. The castings C are suitably recessed in their sides to receive the ends of the bars, and are lipped thereover, as shown, to make a strong and rigid connection. The end bars of the truck-frame are also composed of two parallel flat bars D D, set edgewise and secured at their ends to castings C below bars A A, as shown.

Each casting C has an inwardly-extending portion c extending between bars A toward the pedestals, and in the extremity of said portion is an inclined slot c', in which is an adjustable wedge E, that may be formed with

a threaded tang E², as in Fig. 13, or have a bolt E' run therethrough, as in Fig. 3. The upper ends of the end braces F enter slots c' and abut against wedges E. Preferably the end braces are composed of parallel bars set edgewise, their lower ends engaging a recess b in the foot of the adjoining pedestal, while their upper ends are formed into or connected to a wedge-shaped head-block F', which fits against the oppositely-inclined face of wedge E. By simply tightening the nut on bolt E' or shank E² the braces can be stiffened or adjusted to any load to be placed on truck. 65

Below bars A and between and connecting the lower ends of adjoining pedestals B are foot-bars, each composed of two parallel bars G set edgewise, and attached to the pedestals by bolts g, as shown. To the center of bars A is secured a casting II, over which is strung a rod h, the ends of which pass through openings in castings I, secured to and between bars G, nuts h' being placed on the ends of rod h to enable the rod to be tensioned. The object 75 of this rod is to stiffen the upper bars A and brace them from bars G, when weight is put upon the outer ends of the truck-frame.

A spring J is placed in each pedestal between bars A, its ends projecting beyond the pedestal and below bars A, as shown. The springs are separately semielliptic, and their outer ends are connected to the upper ends of inclined links j, the lower ends of which are secured in suitable recesses k' in projections k on the lower ends and sides of axle-boxes K, which are otherwise of ordinary construction, journaled on axles X. The upper ends of links j are preferably concaved, as shown at j', Fig. 6, to receive the eyes on the 90 ends of the springs, the concavities j' being so formed as to relieve the pivot-bolts j² of the strain which they would have to bear if the spring were connected to the links by hinge-joints. It will be observed that this arrangement of springs and vibrating or swinging links constitutes a toggle-spring mounting of the truck-frame upon the axle-boxes, the links permitting the freest movement of the springs and preventing any sudden shocks 95 being transmitted to or from the truck-frame. 100

As an additional precaution in very heavy trucks coiled springs J' may be secured in castings J², attached to bars A directly over

- the ends of springs J, (see Fig. 1,) so that if the truck be very heavily loaded they will supplement springs J. However, I do not propose to use these supplementary springs 5 on all trucks, the essential features being the spring attached to pedestal or frame, and the swinging links connecting spring to axle-box.
- In Fig. 8 a metal yoke-strap J⁴ is shown which runs over top of spring J and under bars 10 A to support the latter on the spring. In Fig. 9 I show two similar yokes J⁵, connected at top by a bar J⁶, against which the spring bears; in Fig. 10 a metal bar J⁷, with offset to receive the boss of spring, the ends of bar J⁷ 15 bearing against the under side of the top of pedestal, as shown. In Figs. 8, 9, and 10 the top of pedestal is cut out to accommodate the yokes and straps. The end bars D are trussed by rods D', which pass under castings d and 20 through suitable openings in castings C, as shown. To the centers of end bars D is secured a step-casting d, upon which is supported the bolster-spring L, the ends of which spring are connected by hangers or yokes to 25 the side sill or bolster of the car-body, as indicated in the drawings.

In Fig. 2 angular castings M are bolted to the side sills Y of the car-body, said castings having inwardly-projecting ears M', to which 30 are hinged the lower ends of hangers m, the upper ends of which are pivoted to the ends of bolster-spring L, as shown, thus suspending the body in a secure but easy manner upon the truck. From the ears M' of each 35 casting M depends a tubular sleeve M², through which passes a king-bolt N, that also passes into and through a tubular casting O, secured between the end bars D, adjoining the corner casting C', as shown. The upper 40 end of casting O is provided with a shallow internal flange O', that forms a bearing for a coiled spring n, surrounding the lower end of bolt N, and secured thereon by a washer n² and nut n', as shown. The springs n on the 45 king-bolts N would oppose the spring L, but they are to be adjusted simply to prevent oscillation or tetering of the body on the springs L, and this they effectually accomplish. There being four king-bolts at the corners of the 50 car both longitudinal and lateral oscillation of the body is prevented. Coiled springs l may be placed around the sleeve M² of the castings to reinforce the spring L.

In Fig. 12 the casting M is replaced by an 55 angular casting P, having a downwardly-projecting horn P', onto which is hooked the lower end of an S-shaped socketed hanger p, the upper end of which is recessed to receive the end of spring L, much like the ends of 60 links j are recessed, as above described.

In Fig. 11 I have shown how the parts are arranged when the car is provided with transverse sills y. Then castings Q take the place of castings M, said castings being provided 65 with ears for attachment of links m, and with

openings for the passage of king-bolts N, as shown.

In Fig. 7 the levers I are pivoted by bolts to the pedestals and to the springs.

I do not confine myself to the location of 70 the adjusting-wedge blocks described at the upper end of the braces, as in some cases they might be located at the lower ends conveniently.

Having thus described my invention, what 75 I claim as new, and desire to secure Letters Patent thereon, is—

1. The combination of the axle-boxes, the 80 vibrating or swinging links connected thereto to opposite sides thereof at their lower ends, the spring supported on and connected to the upper ends of said levers and the truck-frame supported on the spring, substantially as described.

2. The combination of the truck-frame, the 85 pedestals attached thereto, the semielliptical spring lying within the pedestal above the journal-box, and the swinging links connecting the ends of said spring to the journal-box, substantially as described. 90

3. The combination of the truck-frame, the 95 pedestals attached thereto, the spring lying within the pedestal above the journal-box, and the swinging links connecting the ends of said spring to the journal-box, with the coiled springs J' for reinforcing the elliptical spring substantially as described. 90

4. The combination of the truck-frame, the 100 pedestals attached thereto, the semielliptical spring lying within the pedestal above the journal-box, the swinging links connecting the ends of said spring to the journal-box, with the coiled springs J' for reinforcing the elliptical spring with the castings J² attached to the truck-frame above links j, j, and the 105 springs J' for reinforcing the elliptical spring, substantially as described.

5. The combination of the journal-box, the 110 links j connected thereto, having recesses j' in their free ends; with the spring J having its ends engaged in said recesses j' substantially as described.

6. In a truck, the combination of the pedestals, the top side bars A, A, connected thereto, the casting H attached to said bars intermediate the pedestals, the lower side bars G, G, attached to the pedestals, the castings I, I, attached to bars G, and the rod h, connected to castings H and G, substantially as described. 115

7. The combination of the truck-frame, the 120 transverse inverted semielliptic bolster-springs L on the ends thereof, and the swinging-link hangers pivotally connected to the ends of said springs and to castings on the 125 car-body sills, all substantially as described.

8. The combination of the truck-frame, the 130 car-body, and bolster-springs, and the castings on the car-body to which the bolster-spring is connected; with the castings O, at-

tached to the ends of the frame, the king bolts N, loosely connecting castings O and the castings to which the bolster is connected and the springs n on bolts N, substantially as described.

5 9. The combination of the truck-frame, the bolster-springs L on the ends thereof, and the hangers connecting the ends of said spring to casting P on the car-body sills, and the castings O on the truck-frame below castings P, with the king-bolts N, connecting castings O and P, and the springs on said bolts, all substantially as described.

10. In a truck the combination with the end braces, of the adjusting-wedge blocks, substantially as described, for tightening the braces, substantially as described.

15 11. In a truck the combination of the pedestals, the top bars and end castings with the inclined braces as F, and the adjusting-wedge as E, all substantially as described.

20 12. In a truck the combination of the side bars, and pedestals, the corner castings having slots c', adjusting-wedges E' in slots c' with the end braces F, having wedge head-block F' entering slot c and engaging wedge

E, for the purpose and substantially as described.

13. The combination of the truck-frame, the bolster-spring L, the castings M attached to the car-sills, having depending portions M², the hangers connecting the ends of the bolster-spring to said castings, and the springs I surrounding parts m of the castings, for the purpose and substantially as described.

30 14. The combination of the truck-frame, the bolster-spring L, the castings M attached to the car-sills, having depending portions M², the hangers connecting the ends of the bolster-spring to said castings, and the springs I surrounding parts m of the castings, with the casting O, the king-bolts N, and springs n, all for the purpose and substantially as described.

35 15. In testimony that I claim the foregoing as my own I affix my signature in presence of two witnesses.

THOMAS CRAWFORD.
